UNITED STATES PATENT OFFICE.

JOSEPH P. DE BROECK, OF SANTA BARBARA, CALIFORNIA.

CURTAIN WINDOW.

1,418,539.

Specification of Letters Patent. Patented June 6, 1922.

Application filed January 3, 1921. Serial No. 434,463.

To all whom it may concern:

Be it known that I, JOSEPH P. DE BROECK, a citizen of the United States, and a resident of Santa Barbara, county of Santa Barbara, and State of California, have invented a new and useful Curtain Window, of which the following is a specification.

My invention relates to frames for holding glass windows in flexible material.

10 An object of the invention is to provide an improved means with which a glass window may be readily placed in flexible material, such as an automobile curtain, and held securely therein. Another object is the 15 provision of such a device which permits speedy replacement of the broken glass.

The invention possesses other objects and features of advantage, some of which, with the foregoing, will be set forth in the following description of the preferred form 20 of my invention which is illustrated in the drawings accompanying and forming part of the specification. It is understood that I do not limit myself to the showing made 25 by the said drawings and description, as I may adopt variations of the preferred form within the scope of my invention as set forth in the claims.

Referring to the drawings:

30 Fig. 1 is an elevation of my window frame as installed in a section of curtain. Fig. 2 is a similar view showing the frame open and partly detached. Fig. 3 is a sectional view, the plane of section being indicated by the line 3-3 of Fig. 2. Fig. 35 4 shows a modified structure.

My new window comprises a frame which may be circular or any desired contour and formed preferably of two sections 2 and 40 3 hinged together at one side and provided with a snap catch or lock at the other side. The snap lock comprises a spring arm 4 on one of the frame parts, and carries a button 6 adapted to snap into the aperture 7 on 45 the other frame part. The frame parts are thus securely held together but are readily opened when necessary.

The frame is of substantially U-section as indicated in Fig. 3, the outer flange being curved or arched to enclose the glass sheet 8, as shown, and the inner flange be-

ing flat to adapt it to be engaged under an annular flange strip 9 secured to the edge of the curtain or other material 11 by stitches 12. The strip 9 may be of leather 55 or any suitable material stitched or cemented along the edge to the curtain material and lying contiguous therewith. This strip provides a slightly deformable pad on which the glass rests without rattle. I may 60 make this strip of thin metal having spaced tabs 13 crimped permanently upon the material as shown in Fig. 4. In this case I rely on the resiliency of the frame flanges to tightly grip the glass. 65

After attaching the annular flange strip 9, the window is installed by laying the glass 8, cut to proper size, upon the strip, and applying one side 2 of the frame, the flat flange of the frame entering between the 70 material and the annular strip substantially to the line of fastening, and the arched flange overlying the glass. The other half of the frame is then closed on the first half in the same manner, thus securely holding 75 the glass, with a neat strong and readily removable frame. Pressure on the button 6 permits the frame parts to be separated if necessary, when they may be withdrawn for inserting a new glass. 80

I claim:

1. A window for flexible material comprising a flat strip affixed to the material about the window aperture therein and contiguous therewith, a sheet of glass, a frame 85 having hinged sections each formed with an outer flange enclosing the glass and an inner flange lying between the material and said strip, and means for fastening the hinged frame sections together. 90

2. A window for flexible material comprising a flat strip affixed to the material about the window aperture therein and contiguous therewith, a sheet of glass, a frame comprising pivoted sections and formed 95 with an outer flange enclosing the glass and an inner flange lying between the material and said strip, and a releasable spring latch for locking the frame sections together.

In testimony whereof, I have hereunto 100 set my hand.

JOSEPH P. DE BROECK.
